BRAKE

Alvin J. Musselman, Cuyahoga Falls, Ohio

Application March 26, 1931, Serial No. 525,527

4 Claims. (Cl. 188—152)

The invention relates to brakes, and has, among its other objects, the provision of improved brakes which are durable, efficient and of simplified construction.

5 One form of the invention is embodied in a bag which comprises an internal expanding brake band, the brake band being frictionally engageable with the inner surface of a member which functions as a brake drum. The ends of the 10 brake band normally abut against shoulders provided upon a tubular trunnion which extends into the brake drum, the construction being such that the trunnion holds the brake band against rotation while the brake drum is normally free to rotate. Slidably journaled in the trunnion and also 15 abutting the ends of the brake band are a pair of bars which may be displaced to expand the brake so that it will effectively engage the brake drum and prevent or retard rotation thereof. Disposed between the bars is a sack or bag which is 20 preferably formed from resilient material, such as rubber, and it is filled with a suitable fluid, the bag or sack being connected to suitable means whereby the fluid within the bag or sack may be 25 made to expand the bag to displace the bars. A tube leading into one end of the bag or sack connects it with the means for causing the fluid to expand the bag or sack, and a tube leading out 30 of the other end of the bag may be utilized to fill the bag and the braking system with the fluid.

Brakes embodying the invention comprise relatively few parts and the construction is such that there is very little danger that leaks will develop to render the brakes functionally inoperative.

In the preferred embodiments of the invention, very little clearance is left between the surface on the brake drum. This insures that the bag of resilient material will not be subjected to excessive strains or stresses as it is only necessary to expand it a very small amount to have the brake function.

Other advantages of the invention will become apparent as the following detailed description progresses, reference being had to the accompanying drawing, wherein:

Figure 1 is a central longitudinal section taken through the hub portion of an aeroplane wheel, braking apparatus embodying the invention being disposed within the hub, and

Fig. 2 is a section taken on line 2—2, of Fig. 1.

Referring to the drawing wherein a preferred embodiment of the invention is illustrated, the reference character 10 designates generally the hub of an aeroplane wheel. In this instance, the

hub comprises a sleeve 11 which also functions as a brake drum. Mounted on the ends of the sleeve 11 are flanges 12 which are adapted to hold a pneumatic tire (not shown) in place upon the sleeve. The sleeve 11 is journaled in ball-bearings 13 and 14, the ball-bearings 13 and 14 being mounted upon a tubular trunnion 15 which is fixed to the framework of the aeroplane (not shown). Projecting through the trunnion 15 is a tubular shaft 16 which is also held against rotation.

Disposed within the sleeve 11 and frictionally engageable with the inner surface thereof is an internal expanding brake band 18 which has its ends enlarged, as indicated at 19. The ends 15 19 of the brake band normally abut against shoulders 20 formed upon the trunnion 15, the construction being such that when both ends 19 abut against the shoulder 20, the brake 18 does 20 not effectively engage the inner surface of the combined brake drum and sleeve 11.

Slidably journaled within a slot 22 formed in the drum 15 are bars 23 which also abut against the ends 19 of the brake drum. As shown, each bar 23 is preferably provided with a bead 24 extending longitudinally thereof, the bead being received within a groove 25 formed in the associated end 19.

A bag 27 disposed within the slot 22 and between the bars 23 is formed from flexible material. Thus the bag 27 is preferably formed from a resilient material, such as rubber. The bag is preferably rectangular in cross-section and preferably extends from adjacent one end of the brake band 18 to adjacent the other end.

Metallic tubes 28 and 29 project from the ends of the bag and are securely fixed thereto in such manner that fluid tight joints are provided between the tubes and the bag. A tube 30 coupled to the outer end of the tube 28 provides means 40 whereby the bag may be operatively connected to any suitable means (not shown) for causing the contents of the bag to expand it and thus displace the bars 23 away from each other so that they will expand the brake band 18.

The bag 27 may be filled with any suitable fluid, liquid being preferably employed.

The outer end of the tube 29 is normally closed by a cap 33 but the cap may be removed to bleed the system, or to permit the system to be filled 50 with liquid.

The brake is preferably of the "self-energizing" type. That is, if the sleeve 11 is rotating in a clockwise direction (Fig. 2) and the brake band is expanded, the action of the sleeve 11

on the brake band is such that the right-hand end 19 (Fig. 2) will be driven against the adjacent shoulder 20, and continued rotation of the sleeve will tend to expand the band 18 and cause it to more effectively engage the inner surface of the sleeve. Obviously, when the sleeve 11 is rotating in a counter-clockwise direction and the brake band is expanded, the same action takes place, but in this instance the left hand end 19 (Fig. 2) is driven into engagement with the shoulder 20 associated with it.

While I have shown and described certain embodiments of my invention, it is to be understood that it is capable of many modifications. Changes, therefore, in the construction and arrangement may be made without departing from the spirit and scope of the invention as disclosed in the appended claims, in which it is my intention to claim all novelty inherent in my invention as broadly as possible, in view of the prior art.

What I claim as new, and desire to secure by Letters Patent, is:

1. The combination with a trunnion member having a slot therethrough, of a brake drum rotatably mounted thereon, a brake band disposed around said trunnion member and frictionally engageable with said drum, the ends of said brake band registering with said slot, bars slidably journaled in said slot and directly engageable with the ends of said brake band, and means for displacing said bars relative to each other to force the brake band into effective engagement with said brake drum.

2. The combination with a trunnion member having a slot extending therethrough, of a brake drum rotatably journaled on said trunnion member, a brake band disposed around said trunnion

member and frictionally engageable with said brake drum, the ends of said brake band registering with said slot, bars in said slot, said bars being engageable with the ends of said brake band and having flat surfaces slidably engaging the surfaces of the slot, a flexible bag disposed between said bars, and means for connecting said bag to a source of fluid under pressure.

3. The combination with a hollow trunnion member having a slot extending through its wall, of a brake drum rotatably mounted on said trunnion member, a brake band disposed around said trunnion member and frictionally engageable with said brake drum, the ends of said brake band registering with said slot, means including a flexible bag disposed in said slot for displacing the ends of the brake band to expand it, and a tube extending through said hollow trunnion member for connecting said bag with a source of fluid under pressure.

4. In combination, a brake drum, a trunnion, anti-friction devices carried by said trunnion and rotatably journaling said brake drum, said trunnion being provided with a slotted enlarged portion intermediate the ends of said brake drum, a brake band disposed around said trunnion member and frictionally engageable with said brake drum, the ends of said brake band registering with said slot in said enlarged portion, elongated bars in said slot, said bars being disposed parallel to the axis of rotation of said brake drum and being engageable with the ends of said brake band, and means disposed in said slot between said bars for displacing them relative to each other to actuate said brake band.

ALVIN J. MUSSELMAN.
